UNITED STATES PATENT OFFICE.

WILLIAM A. DUNLAP, OF PITTSBURGH, PENNSYLVANIA.

SHADE HOLDER.

Application filed August 27, 1927. Serial No. 215,820.

My invention refers to improvements in shade holders, particularly adapted for use with electric lamps.

Ordinarily, shades of glass or other fragile or breakable material are clamped in position within or upon a supporting base or frame by means of a clamp or binding screws. These frequently exert excessive or unequal strains on the rim of the shade, tending to 10 fracture or breakage.

In my invention I provide a plurality of inwardly located outwardly acting resilient grasping or binding fingers, by which the shade is supported in engagement with its holding ring or frame, and whereby any such 15 damaging strains are avoided.

The improvement consists of a plurality, preferably three screw-actuated resilient fingers properly mounted and located in the 20 manner more fully hereinafter described and as shown in the drawings.

Referring to the drawings:

Fig. 1 is a view in elevation of a shade and its holder in operative position;

Fig. 2 is an enlarged vertical sectional detail view, showing one of the resilient clamping fingers in holding engagement with the shade;

Fig. 3 is a similar view, showing the finger 30 released;

Fig. 4 is an inner face view of the finger of Fig. 2, and its mounting;

Fig. 5 is an enlarged transverse sectional view on the line V—V of Fig. 2.

In the drawings, A is the shade holder or skirt surrounding and connected with the usual lamp socket to which current is supplied through the usual attaching fixture 2. The holder A is adapted to surround the lamp 40 socket and the lamp, as indicated in dotted lines in Fig. 1, and to also carry the lower shade B, by the means constituting the present improvement.

The holding means for the shade consist of 45 a plurality of inner resilient fingers or prongs 3 of light sheet metal, curved in the manner shown and provided intermediate of their ends with the pivoting lugs 4. The lower or binding portion of the arm or tongue 3 is rounded, as at 5, so as to bear upwardly underneath and against the inner curved portion of the top of the shade B, as in Fig. 2.

The upper portion of the holding tongue,

beyond the integral pivoting lugs 4, extends upwardly with a slight inward curve, as at 55 6, providing means for actuating the arm by slotted engagement therewith. For such purpose the upper portion of the arm is centrally slotted, as at 7, providing for insertion therein of the reduced neck 8 of an actuating 60 set screw 9, having the inner retaining terminal head 10 and the outer thumb screw head 11.

The pivoted arm 3 is mounted by its lugs 4 between the inwardly extending hinge supports 12 of bracket 13. Said bracket, as shown in Fig. 5, is made of a U-shaped piece of sheet metal which is held against the inner side of the depending wall 14 of the holder A, by spot welding or other suitable means, 70 and also by the central screw engaging nut 15.

The latter provides a nut mounting for the threaded stem 9, and has an inwardly extending reduced retaining neck 16 which passes through the wall 14 and the rear wall 75 of bracket 13, and is riveted thereover on its inner side, as at 17.

By means of such construction, supplemented by the spot welding connection referred to, the bracket 13 is firmly held in position by the screw mounting.

Lugs 4 are pivotally connected with the terminals 12 of bracket 13 by the cross pin 18, so that upon adjustment of the screw 9 the arm 3 may be thrust outwardly or inwardly, to clamp or release the shade B.

By reason of the light resilient character of the fingers, and their rounded engagement against the inner upper sides of the shade, there is no positive or excessive pressure exerted against the shade tending to fracture or undue binding, with sufficient resiliency to compensate for any excessive pressure by either screw.

The screws as shown are mounted at suitable locations around the depending rim 14 of the holder A in any suitable number, preferably three, equidistantly spaced, and the construction facilitates easy placement or removal of the shade by merely loosening or 100 tightening the several thumb screws.

The device may be used with any design, shape, or material of shade construction, either glass, porcelain, or enameled sheet metal, with equally good results.

The exact proportions or features of the

invention may be variously changed or modified by the skilled mechanic, but all such are to be understood as within the scope of the following claims.

5. What I claim is:

1. The combination with a shade holder, of an inwardly extending double sided bracket, a resilient binding arm pivotally mounted between the sides of the bracket, means connecting the bracket with the shade holder, and an actuating set screw extending through said connecting means engaging the arm.
10. The combination with a shade holder, of an inwardly extending double sided bracket, having downwardly extending terminals, a curved resilient holding arm pivotally
- 15.

mounted between the terminals of the bracket and provided with a slotted terminal, and an adjusting screw having a reduced terminal neck engaging the slotted portion of the 20 arm.

3. The combination with a shade holder, of a double sided bracket extending inwardly from the shade holder, a holding nut fastening the bracket to the shade holder, a curved 25 resilient arm pivotally mounted between the sides of the bracket and provided with a slotted terminal, and an adjusting screw engaging the nut and having a reduced terminal neck engaging the slotted portion of the arm. 30

In testimony whereof I affix my signature.

WILLIAM A. DUNLAP.
